WOMAN'S GARMENT

Patrick J. Moran, Newark, N. J., assignor to
Irving Rosner, New York, N. Y.

Application September 17, 1935, Serial No. 40,966

5 Claims. (Cl. 2—42)

This invention relates to a woman's garment and more particularly to a brassière and has for its object to provide a new and improved garment of this type capable of being adjusted to support and mold the busts of a woman in a variety of different ways.

A further object of the invention is the provision of a brassière constructed in a novel manner so as to permit the busts to be accentuated in any particular position suited to the needs of the wearer.

A still further object of the invention is to provide a pair of floating bust pouches resiliently attached to the brassière at several points and capable of being adjusted with relation to the brassière.

With the above and other objects in view, as will be presently apparent, the invention consists of certain novel details of construction and combinations of parts hereinafter fully described, illustrated in the accompanying drawing and specifically claimed.

In the accompanying drawing like characters of reference indicate like parts in the several views, and:

Figure 1 is a front view of the garment.

Figure 2 is an inside view thereof.

Figure 3 is a view of the bust pouches detached from the brassière.

Figure 4 is a section on line 4—4 of Figure 1.

Figure 5 is a section on line 5—5 of Figure 3.

Figure 6 is an enlarged detail view of an upper portion of the brassière.

Figure 7 is a detail of the shoulder straps.

Referring to the drawing in detail, numeral 1 designates the brassière, 2 the pouch construction and 3 the resilient tapes for attaching the bottom of the pouch construction to the lower edge of the brassière. The brassière comprises a belt portion 4 which fits around the chest of the wearer. Attached to one end thereof is a short resilient tape 5 provided with fastening means 6 adapted to cooperate with the fastening means 7 secured to the opposite end of the belt portion for holding the garment in place around the body of the wearer. Inserted in the belt portion is a soft lace like piece 8. This piece is so cut and fastened at the seams 9 and 10 that the central points 11 and 12 will bulge outwardly to accommodate the curvature of the busts.

The pouch construction 2 includes two pockets 13 and 14 for accommodating the busts. Both pockets are formed alike and with the meeting ends overlapping and fastened together at the points 15. The upper edges 16 and 17 of the

pockets are cut on a curve. The curvature of the edges 17 are on a larger radius than the curvature of the edges 16 and are arranged on a lower level than the edges 16. As best seen in Figure 3 a resilient strap 18 connects the upper ends of the pockets together. Permanently attached to the upper points 19 and 20 of the pockets are non-stretchable ribbons 21. These ribbons pass through loops 22 fastened to the ends of the straps 23 sewed at the opposite end 10 at 24 to the highest points 25 of the belt portion. Shoulder straps 26 connect the straps 23 to the rear of the said belt portion. Adjusting elements 27 are provided to lengthen or shorten the shoulder straps to suit the needs of the wearer. A short end portion 28 of the shoulder straps are made of rubber material in order to provide resiliency to the said straps.

As will be seen from Figure 2 the height of the pockets 13 and 14 can be adjusted relative to the position of the belt by lengthening or shortening the shoulder straps. As the belt fits stationary on the body of the wearer any tension or slackening of the shoulder straps will only effect the pouch portion or pockets. Thus if a woman is disfigured with drooping busts this deformity can be corrected by tensioning the shoulder straps so that the pockets will be pulled up. Likewise a substantial amount of side movement in addition to the up and down movement of the pockets can be had by slipping the end 29 of the strap 23 either to the left or right. For example if the end 29 of the strap is moved to the extreme left the pocket 13 will move in the same direction and vice versa if the strap is moved to the extreme right the pocket will move in that direction. It will therefore be seen that in addition to providing means to move the breasts in a vertical position means are also provided to move them in a lateral position.

There has thus been provided a simple and efficient device of the kind described and for the purpose specified.

It is obvious that changes may be made in the form and construction of the invention without departing from the principles involved therein. It is not, therefore, desired to confine the invention to the exact form herein shown and described, but it is desired to include all such as come within the scope of the appended claims.

Having described my invention, I claim:

1. In a garment of the class described, a belt portion, a pouch portion behind said belt portion, said pouch portion including two pockets, means to resiliently connect the bottom of said pouch

portion to said belt portion and means to adjust the position of said pouch portion in relation to said belt portion.

- 5 2. In a garment of the class described, a belt
adapted to fit around the chest of the wearer and
provided with a pair of inserts shaped to fit the
contour of the bust, a pair of pockets behind
said inserts, each of said pockets including two
wall members, the upper edges of said wall mem-
bers 10 left open and cut on a curve, the edge of
the wall members adjacent said inserts arranged
on a higher elevation than the other wall mem-
bers, resilient straps for connecting the lower
edges of said pockets to said belt, and shoulder
straps for supporting said belt and said pockets.
15 3. In a garment of the class described, a pouch
portion, said pouch portion including two pockets,
each of said pockets including two wall mem-
bers left open at the top, the top edges of one
of said wall members arranged on a higher eleva-
tion than the edges of the other wall members,
and means to join said pockets together.
20

4. In a garment of the class described, a pouch
portion, said pouch portion including two pockets,
each of said pockets including two wall mem-
bers left open at the top, the top edges of one
of said wall members arranged on a higher ele-
vation than the edges of the other wall members,
a resilient strap member for connecting the top
of said pockets together, the lower portions of
said pockets overlying each other and joined
together. 10

5 5. In a garment of the class described, a pouch
portion, said pouch portion including two pockets,
each of said pockets including two wall mem-
bers left open at the top, the upper edges of
both of said wall members cut substantially on 15
the same curvature, the edge of one of the wall
members arranged on a higher elevation than
the curvature of the other wall member, and
means for attaching said pockets together. 10

PATRICK J. MORAN. 20
